UNITED STATES PATENT OFFICE.

FRANK C. HULSE AND LESLIE S. UPHOFF, OF SCHENECTADY, NEW YORK.

BLACKBOARD-COMPASSES.

1,121,503.

Specification of Letters Patent. Patented Dec. 15, 1914.

Application filed March 31, 1914. Serial No. 828,578.

To all whom it may concern:

Be it known that we, FRANK C. HULSE and LESLIE S. UPHOFF, citizens of the United States, residing at Schenectady, in the county of Schenectady and State of New York, have invented new and useful Improvements in Blackboard-Compasses, of which the following is a specification.

The invention relates to a compass, and more particularly to the class of drafting compasses adapted for use in connection with blackboards in schools, colleges or elsewhere.

The primary object of the invention is the provision of a compass wherein the legs thereof are constructed to permit the projecting of the marking material and also to permit the fixed or anchoring point to be held firmly to the blackboard or other marking surface.

Another object of the invention is the provision of a compass of this character wherein the marking material when projected will be firmly held against slipping action within the leg of the compass.

A further object of the invention is the provision of a compass wherein the fixed or anchoring point revolvably supports the leg holding the marking material so that the compass can be conveniently manipulated without the anchoring or fixed point mutilating the writing surface of the blackboard or the like when the instrument is in use.

A still further object of the invention is the provision of a compass which is simple in construction, novel in form, reliable and efficient in its purpose, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawing:—Figure 1 is a side elevation of a compass constructed in accordance with the invention. Fig. 2 is an enlarged fragmentary side elevation of one leg of the compass, the same being partly in section.

Fig. 3 is a fragmentary vertical sectional view on an enlarged scale of the other leg of the compass. Fig. 4 is a fragmentary side elevation on an enlarged scale of a modified form of the leg of the compass.

Similar reference characters indicate cor-

responding parts throughout the several views in the drawing.

Referring to the drawing in detail, 10 and 11 designate the respective legs of the compass, which are swingingly connected together by means of a pivot 12 so that the legs can be spread apart or brought close together as the occasion may require in the use of the compass. The leg 10 at its free end portion forms a socket to receive a stick 65 C of marking material and is provided with one or more longitudinal slots L so that the said free ends of the legs can expand and contract for the freeing or clamping of the stick C therein. Slidably fitted on the leg 70 10 is a clamping sleeve T having a slightly outwardly flared end D which co-acts with an enlargement U at the free end of the leg 10 to compress the same into clamping relation to the stick C held within the leg. The 75 opposite or inner end of the sleeve T is formed with a cam edge N which is adapted to engage a pin P fixed in the leg 10 so that on the turning of the sleeve T the same will be moved onto the enlargement U for compressing the free end thereof against the stick C. On turning the sleeve T in the reverse direction the same will work off of the enlargement U at the free end of the leg 10, 80 permitting it to expand for releasing the 85 stick C so that it may be removed or adjusted as may be required.

Slidably fitted within the leg 10 rearwardly of the stick C is an ejector pin R which has fitted therein a finger lug K projected through an elongated slot S formed in the leg 10 so that the pin R can be manually moved, which is designed to act upon the stick C to project it from the leg 10 when the free end of the latter is expanded, 90 and in this manner the said stick can be readily adjusted or removed from the leg 10 of the compass.

The other leg 11 of the compass is socketed to receive the reduced stem W of an 100 anchoring tip Z which carries in its free end a rubber anchoring point V which is fixed therein in any suitable manner, it being understood of course that the point V may be made from other material if found 105 desirable. The stem W of the tip Z is formed with an annular slot G into which projects a retaining pin Y, the latter being mounted in the leg 11, and in this manner the said tip is swiveled in the latter, 110

thus in manipulating the compass the tip Z will remain stationary while the other portion of the compass will revolve thereon.

In Fig. 4 there is shown a slight modification of one of the legs of the compass where-in the leg 13 has fixed thereto the extension 14 of a chalk holder comprising a barrel O which is angularly disposed with respect to the leg 13, and has fitted therein a tube A 10 which is formed with one or more slots E longitudinally disposed therein, and into this tube is fitted the stick C' of suitable writing material or chalk.

Formed in the barrel O is a cam slot B, 15 while mounted in the tube A is a finger knob H which projects through the cam slot B and is guided therein to project or retract the tube A without or within the barrel, and in this manner the split end of the tube A 20 is expanded or compressed for the freeing or clamping of the chalk therein. It is of course to be understood that the stick C' is of greater cross sectional diameter than the inner diameter of the tube A so that when 25 the stick is inserted therein it will expand the split end thereof so that when the said tube is contracted within the barrel the split end will be compressed for the clamping of the chalk in the tube.

30 From the foregoing it is thought that the

Copies of this patent may be obtained for five cents each, by addressing the "Commissioner of Patents, Washington, D. C."

construction and manner of use of the device will be clearly understood, and therefore a more extended explanation has been omitted.

What is claimed is:—

1. In a compass, a leg having a split end, 35 a sleeve slidably and rotatably supported on the split leg and having a cammed inner edge, a pin fixed in the end and working against the cam edge of the sleeve, and an enlargement formed at the split end of the leg and adapted to be traversed by the sleeve for compressing the split end of the leg. 40

2. In a compass, a leg having a split end, 45 a sleeve slidably and rotatably supported on the split leg and having a cammed inner edge, a pin fixed in the leg end and working against the cam edge of the sleeve, an enlargement formed on the split end of the leg and adapted to be traversed by the sleeve for compressing the split end of the leg, an ejector pin slidably fitted within the leg, and means carried by the pin and projected exteriorly of the leg for moving said pin. 50

In testimony whereof we affix our signatures in presence of two witnesses.
